UNITED STATES PATENT OFFICE.

ALFRED PAGE, OF GEORGETOWN, SOUTH CAROLINA.

WAGON-STANDARD.

SPECIFICATION forming part of Letters Patent No. 678,303, dated July 9, 1901.

Application filed May 1, 1901. Serial No. 58,357. (No model.)

To all whom it may concern:

Be it known that I, ALFRED PAGE, a citizen of the United States, residing at Georgetown, in the county of Georgetown and State of South Carolina, have invented certain new and useful Improvements in Wagon-Standards; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to wagon-standards, and has for its object the provision of a simply and durably constructed standard which is adapted for ready attachment to existing as well as new wagon-bolsters and which when in place is firmly supported against sidewise and endwise movement.

20 The details of construction of my improved standard are set forth in the following description, in connection with which attention is called to the accompanying drawings.

25 In the drawings, Figure 1 is a perspective view of a standard embodying my invention shown as applied to a bolster. Fig. 2 is a vertical sectional view on line 2 2 of Fig. 1. Fig. 3 is a vertical sectional view on line 3 3 of Fig. 1.

30 Referring to the drawings by letter, A denotes the bolster, which may be of the usual construction. On the top of the bolster is secured a plate B, the width of which is preferably equal to the width of the bolster.

35 The standard C, which is built up as shown, is provided with depending portions c c, which flank the bolster, and c' c' are inward extensions of said portions, which terminate in a loop c², said loop engaging the bolster from beneath, as shown more clearly in Fig. 3. A bolt d is passed through the portions c and bolster and is threaded to receive a nut d'. 40 The standard and depending portions are

made from a single piece of metal, and the inward extensions and the loop are also made from a single piece of metal, the forward ends of the extensions being welded to the depending portions.

45 e is a bolt passed through the extensions c' and bolster, preferably in line with the center of the loop c². e' is a nut for this bolt. The standard has a reduced portion c³ at its outer side, which portion serves as a brace, 55 its lower squared end contacting with the plate B. The bolts serve merely as the attaching means for securing the standard to the bolster. The bolts are not subjected to any strain other than that exerted in a direction longitudinal with the bolster, and there is no tendency, therefore, of the bolster to split and weaken, and thus impair the usefulness of the standard. The loop c² receives the strain when pressure is brought to bear on 60 the standard and effectually supports the latter against movement, aided by the brace portion c³. The standard may be inexpensively made and may be applied to new or to existing wagon-bolsters without the exercise 65 of particular skill.

70 I claim as my invention—

75 The combination of a plate secured to the top of the bolster, a standard formed of metal bent upon itself and provided with depending portions flanking the bolster, integral inward extensions of said portions, an integral continuous loop at the end of the extensions engaging the under side of the bolster, and a brace portion secured between 80 the standard members and having a lower squared portion contacting with the plate.

85 In testimony whereof I affix my signature in presence of two witnesses.

ALFRED ^{his} PAGE.
